UNITED STATES PATENT OFFICE.

JOHN J. MULVANEY, OF CINCINNATI, OHIO, ASSIGNOR TO WILLIAM A. RINCKHOFF, OF CINCINNATI, OHIO.

BOTTLE-STOPPER.

No. 800,867.

Specification of Letters Patent.

Patented Oct. 3, 1905.

Application filed September 19, 1904. Serial No. 225,011.

To all whom it may concern.

Be it known that I, JOHN J. MULVANEY, a citizen of the United States, residing at the city of Cincinnati, in the county of Hamilton and State of Ohio, have invented certain new and useful Improvements in Bottle-Stoppers, of which the following is a specification.

The object of my invention is to produce a simple, cheap, and efficient bottle stopper or closure which can be removed from the bottle-mouth without the use of the bottle-openers or instruments or devices for removing the bottle stopper, closure, or cap as now used.

My stopper or closure can be removed by simply exerting pressure, striking or forcing the bottle up against any permanent object, the pressure or force exerted against the stopper or cap denting it or forcing the metal inward, this operation forcing the annular lower crimped edge of the cap off of the mouth of the bottle. Thus the cap or stopper can be picked off or will fall of its own accord.

The stopper consists of a metal cap and a gasket made of cork, rubber, or equivalent material. This gasket is placed inside the cap and rests on the annular mouth of the bottle when in use.

In stoppers now in use the gasket and metal caps are practically flat and lie in juxtaposition. My cap is elevated—that is, extends or protrudes materially up from the mouth of the bottle—and is strengthened by ribs, projections, or ridges.

In the accompanying drawings, forming part of this specification, Figure 1 is a view in elevation of the bottle, partly broken away, with my bottle-stopper in place and on the bottle, the bottle mouth and stopper being partly broken away to show the construction.

Fig. 2 is a view in elevation of a bottle, partly broken away, with my stopper in place, the mouth of the bottle and part of the stopper being partly broken away to show the construction, the cap being bent in or dented, the sides of the stopper being loosened up ready to drop off, the force of the blow on the stopper having loosened up the cap. Fig. 3 is a top view looking down on the bottle and stopper in place; and Fig. 4 is a top or plan view of a stopper after my invention, instead of annular ridges being present in the caps curved or irregular ridges being used.

A represents the bottle, and B the bottle-neck.

C represents the metal cap, and D the gasket of the stopper or closure. This cap C is of peculiar shape—that is, elevated, semicircular, or of pyramid shape—and extends up materially from the bottle-mouth, leaving a space between it and the gasket D. The cap C is provided with ridges, ribs, or projections E to strengthen the cap. I may provide as many of these ridges as desired. These ribs are usually annular or surround the cap; but I may make them short, running from the center to the edge of the cap, as shown in Fig. 4. I may dispense with them entirely, if I desire. At its lower edge F the cap is corrugated, as shown.

The gasket D consists of a disk or annular piece made of cork, rubber, or equivalent material. It is about the size of the mouth of the bottle, so that when in place it fits over the entire bottle-mouth. It may be made of any other shape, if desired, and be made of any material and may be fastened in the metal cap C in any desired manner. Instead of being flat, as shown, it may be made semicircular or elevated, as is the cap itself.

At its mouth the bottle A is provided with an annular flange or ring G. The corrugated lower part F of the metal cap G fits over this ring or flange G and is crimped around it. Thus the stopper is held in place. Of course the stopper is put on the bottle with some force, so that the gasket D fits tightly against the bottle-mouth, making an air-tight joint, the crimping being done to hold the stopper in this desired position. When it is desired to open the bottle, a blow or force of any kind is exerted on the cap of the stopper. This of course bends or dents in the cap, the force of the blow or exertion being transmitted to the edge of the cap, where it rests with the gasket edge on the top of the mouth of the bottle, and being weakest from this point down to its crimped edge the blow exerted forces the crimps to relax their hold, as shown in Fig. 2, and the stopper can be removed from the bottle with the hand, or it drops off. It will be readily seen that by the use of my invention bottle-cork pullers, bottle-openers, either hand or machine, are dispensed with.

My improved bottle-stopper can be used on all kinds of bottles and may be connected thereto in any desired manner, the main feature being the elevated, pyramid, cone-shaped, or beehive arch-cap, which extends up materi-

ally from the bottle-mouth, so as to receive a blow and convey the force of the impact to the crimped edge and force its hold off of the bottle-mouth.

5. What I claim as new and of my invention, and desire to secure by Letters Patent, is—

1. In a bottle-stopper, a metal cap, said cap extending up materially above the bottle-mouth, a space being provided between the 10 top of the bottle and the under side of the cap, in combination with a gasket interposed between said cap and the mouth of the bottle and means for holding said cap and gasket on the bottle, as set forth, and for the purposes 15 specified.

2. In a bottle-stopper, a metal cap, said cap extending up materially above the bottle-mouth, a space being provided between the 20 top of the bottle and the under side of the cap; strengthening-ribs formed in said cap, in combination with a gasket interposed between

said cap and the mouth of the bottle, and means for holding said cap and gasket on the bottle, as set forth and for the purposes set forth.

3. In a bottle-stopper, a metal cap, extending up materially above the bottle-mouth, so that a space is provided between the top of the bottle and the under side of the cap, an interposed gasket between the cap and the bottle-mouth, the metal cap being crimped on the bottle-mouth, as and for the purposes set forth. 30

4. In a bottle-stopper, a metal cap, said cap extending up materially above the bottle-mouth, so that a space is left between the bottle-mouth and the under side of the cap, and means for holding said cap on the bottle-mouth, as and for the purposes set forth. 35
